IRVING F. LAUCKS AND CHARLES N. CONE, OF SEATTLE, WASHINGTON, AND THEODORE W. DIKE, OF NEW WESTMINSTER, BRITISH COLUMBIA, CANADA, ASSIGNEES TO I. F. LAUCKS, INC., OF SEATTLE, WASHINGTON, A CORPORATION OF WASHINGTON

METHOD OF HOT GLUING

Application filed April 25, 1930. Serial No. 447,428.

This invention relates to the joining or uniting of pieces or plies and especially where a wood surface is concerned, and more particularly with employment of heat. It is among the objects of the invention to provide an improved method of simplified and direct joining or uniting, making possible a continuous type of operation where desired. Another object is the provision of a method particularly advantageous in the production of composite structures. Another object is to provide improved methods for uniting materials by means of heat-settable adhesives. A further object also is the application of heat for the setting of the adhesive without an undue heating of wood masses remote from the joint surfaces. Other objects and advantages will appear as the description proceeds.

To the accomplishment of the foregoing and related ends, the invention, then, consists of the features hereinafter fully described, and particularly pointed out in the claims, the following description setting forth certain illustrative embodiments of the invention, such being indicative, however, of but a few of the various ways in which the principle of the invention may be employed.

Certain modes of procedure whereby the invention may be performed are exemplified in the drawings wherein:

Fig. 1 is a side view of an apparatus for heating one edge of a block and for pressing blocks together;

Fig. 2 is a top view thereof;

Fig. 3 is an end view of a form of an apparatus for moistening the edge of a block;

Fig. 4 is a side view of an apparatus for disposing powdered adhesive upon the edge of a block;

Fig. 5 is a view similar to Fig. 1, showing two blocks being pressed;

Fig. 6 shows a heating means for blocks;

Fig. 7 shows several heated blocks being pressed with several coated blocks;

Fig. 8 is an end view of an apparatus for forming plywood;

Fig. 9 is a side view thereof; and

Fig. 10 is a side view of an apparatus in-

cluding means for holding or pressing assembled members.

In gluing by the present method, the formation of the bond is accomplished by setting the adhesive by heat and with pressure; however the heat is applied in a manner not complicating the pressing procedure. The adhesive base may be applied to at least one of the surfaces to be joined, and such heat as is to be employed is stored or provided before the pressing, by initially heating at least one of the pieces concerned. Such heating may be applied in any convenient manner, as by conduction, for instance from a heating member contacting with a piece to be glued, or by radiation directly upon one or more of the surfaces concerned.

Adhesive suitable are more particularly materials settable by heat, as for instance, casein, blood, vegetable protein, proteinous seed flours such as soya bean flours, hemp, castor, cottonseed, peanut, sesame, perilla, linseed, rape seed, copra, also in some cases animal glue, starch, dextrine, etc. Preferably, the adhesive base is supplied in non-dispersed form or in discrete particle form. In the use of many of the commonly employed adhesives, including those exemplified, a plasticizing agent, such for example, as a softening fluid is required to develop adhesion. It is to be understood, however, that the invention in its broader aspects, contemplates the use of heat-settable adhesives of a variety of types. The ordinary procedure with adhesives of the type requiring the presence of a plasticizing agent is to utilize water, although in some instances other fluids or substances becoming fluid with heat may be employed, such as alcohol, acetone, creosote oil, phenols, naphthols, etc. In the latter connection reference is made to the copending application of Theodore Williams Dike, Serial No. 594,396, filed February 20, 1932.

The softening liquid may be provided before or after the adhesive base, or in some instances along with it as absorbed moisture or as a suspending menstruum.

In the common methods of gluing where a relatively large excess of water is introduced with the glue, corresponding increases in the

time factor are required for eliminating such extra water. In the preferred practice of the present invention, however, the fluid may be kept down to softening requirements, and 5 the necessity of eliminating large surpluses is obviated. With moist surfaces, as for instance sheets as coming from a veneer cutting machine, sufficient moisture may be already present and none need be added. With 10 dry materials, such for instance as dried wood blocks or plies, moisture may be added as indicated. Because small amounts of fluid are used, neither time nor heat is wasted in eliminating useless surplus, and a bond is 15 obtained quickly.

As indicated, whereas in the old hot-press method of gluing it was necessary to transmit the heat through the material and to the glue line, in the present procedure the heat 20 is applied in situ. Conveniently this may be done by preliminarily heating one or more of the pieces to be glued, and the heat may be thus temporarily stored therein. The heat may be applied by contact of a heating member or by a radiating source.

For example, in gluing blocks, the following procedure may be used. Block number 1 or an equivalent series of short blocks with the same width end to end, is placed against a 30 stop 10 (Fig. 1) with its face to be joined perpendicular to a table 11. A heating member 12 is brought into contact with it for a time to store a suitable amount of heat in the face to be joined. Meantime the block number 2 has one of its faces moistened as by drawing it over a roll 13, a portion of the surface of which extends into a water bath 14, as indicated in Fig. 3, and spread with a dry powdered adhesive base, as by being 35 placed under a shaking screen 15 carrying particles of dry adhesives 16 so that, when the screen is shaken, falling particles of the adhesive 17 will come to rest on the surface of the face. The coated face of number 2 is 40 then pressed against the hot face of number 1. The pressing means may be a hot plate such as 12 so that the opposite face of number 2 is simultaneously heated. Such a step is indicated in Fig. 5, the member 12 being 45 pressed against the block 2 upon the application of pressure to a plunger 18 by any suitable means. Block number 3 may be similarly moistened and supplied with adhesive base and then presented to the hot face of 50 number 2, and so on, building up to any desired extent.

As another example: Block number 1 may be heated in a heating chamber 19 (Fig. 6). Block number 2 is moistened on both of its 55 surfaces to be joined and the adhesive base is dusted on, as by contacting first one face and then the opposite face with a roller, such as 13, for example, and presenting both faces to receive falling particles as from a screen 55 15, for example. Block number 3 is heated

the same as number 1. Block number 4 is treated the same as number 2, and so on. These can be quickly assembled thus, as on a table 20 (Fig. 7), for example, and they require holding for only a relatively short 70 time until the joint is set.

As another example: In laying up a laminated structure involving a wood layer, for instance veneer or plywood, to form a three-ply panel, the core for instance may be heated 75 as in a heating chamber 21. The reverse side of each face member is moistened and the adhesive in discrete particle form is supplied, as for example, by means such as illustrated in co-pending application of Theodore Williams Dike, one of the applicants herein, Serial No. 518,944, filed February 28, 1931, one such means being shown in Fig. 8 wherein face plies are passed on a conveyor 22 under an atomizing means 23 and a shaking screen 24. The plies are assembled as indicated in Fig. 8, one coated ply being disposed beneath the hot core and the other reversed and placed above it; and the assembly held under pressure as in a press 25 for such time as until the joints set. Or, the core may be moistened on both sides to be spread with the adhesive base, and the heat may be carried by the face layers.

On account of the relatively short time interval required, the holding or pressing may be accomplished by a continuous feed through a series of close-set press rolls or pressing-belts, which serve at the same time to compress and carry forward to point of delivery. An arrangement embodying press rolls 26 and also a pressing belt 27 is shown in Fig. 10. As will be understood, blocks assembled, pressed and heated on a table 28 in a manner such as before indicated or in any other suitable manner may be held therein. Similarly, assembled panels may be run between such continuously moving apparatus.

An addition agent may also be supplied 110 before, with or subsequent to the application of the adhesive base, and before the pieces are assembled. Such addition agent may be an agent to promote penetration, or an agent to check penetration of a too readily dispersible adhesive such as those highly water soluble, or an insolubilizing agent, or a fungicidal, bactericidal or insecticidal agent or a fire-proofing agent, etc. Examples are:—alkaline compounds, lime, formaldehyde, 115 paraformaldehyde, copper compounds, camphor, beta-naphthol, oil of cedar, ammonium phosphate, borates, etc. A salt affording action on the adhesive and at the same time introducing moisture as water of crystallization is also contemplated, as for instance sodium phosphate and the like.

Other modes of applying the principle of the invention may be employed, change being made as regards the details described, pro-

vided the features stated in any of the following claims, or the equivalent of such, be employed.

It is to be understood that by the term 5 "setting" and the like in the appended claims is meant producing a permanent alteration in the character of the adhesive by heat or by heat with pressure which renders the adhesive materially less soluble by heat or by 10 other media than it was before it was subjected to the action of heat.

It is also to be understood that while certain types of adhesives have been specifically 15 enumerated by way of example, the invention contemplates the use of the stored heat principle in the application to any adhesive of heat sufficient to render the same materially less soluble.

Reference is made to following applications of Theodore Williams Dike, one of the applicants herein, directed to related subject matter: Serial No. 335,998, filed January 29, 1929; Serial No. 454,832, filed May 22, 1930; Serial 20 No. 455,977, filed May 26, 1930; Serial No. 25 455,978, filed May 26, 1930; Serial No. 456,813, filed May 28, 1930; Serial No. 456,814, filed May 28, 1930; Serial No. 518,944, filed February 28, 1931, referred to above; and Serial No. 538,983, filed May 21, 1931; 30 and Serial No. 565,930, filed September 29, 1931, and Serial No. 594,396, filed February 20, 1932, referred to above.

We therefore particularly point out and distinctly claim as our invention:

35 1. A method of gluing, comprising setting the adhesive by heat and pressure, the heat for such setting having been stored in at least one of the members joined previous to the application of pressure.

40 2. A method of gluing, comprising providing heat for setting the adhesive by storing such heat in a surface to be joined, supplying an adhesive, assembling, applying pressure, with the adhesive in the presence of a fluid 45 in amount not exceeding softening requirements therefor, and setting the adhesive by the stored heat.

3. A method of gluing, comprising storing heat in a piece to be united, supplying an adhesive base in discrete particle form, assembling, applying pressure, with the adhesive in the presence of a plasticizing agent, and setting the adhesive by the stored heat.

45 4. A method of gluing, comprising storing heat in a surface to be joined, supplying an adhesive base in discrete particle form and an adhesive-softening fluid, assembling, applying pressure, and setting the adhesive by the stored heat.

50 5. A method of gluing, comprising storing heat in a piece to be joined, supplying a softening fluid and an adhesive to another piece, assembling, applying pressure, and setting the adhesive by the stored heat.

55 6. A method of gluing, comprising storing

heat in a piece to be joined, supplying a softening fluid and an adhesive to another piece, assembling, applying pressure with the adhesive, and setting the adhesive by the stored heat, said fluid being supplied in an amount 50 not exceeding the softening requirements of the adhesive.

7. A method of gluing, comprising storing heat in a piece to be joined, supplying an adhesive base in discrete particle form to another piece, assembling, applying pressure, and setting the adhesive by the stored heat. 75

8. A method of forming composite bodies, comprising storing heat in a piece to be joined, supplying an adhesive to another piece, forwarding the second piece against the first piece and thereby applying pressure, and setting the adhesive by the stored heat. 80

9. A method of forming composite bodies, comprising storing heat in a piece to be joined, 85 supplying an adhesive in powdered form to another piece, forwarding the second piece against the first piece and thereby applying pressure, with the adhesive in the presence of a fluid in amount not exceeding softening requirements therefor, and setting the adhesive by the stored heat.

10. A method of forming composite bodies, comprising storing heat in a piece to be joined, 90 supplying to another piece an adhesive base in powdered form, forwarding the second piece against the first and thereby applying pressure, with the adhesive in the presence of a softening fluid, and setting the adhesive by the stored heat. 95

11. A method of forming composite bodies consisting of more than two members, which comprises storing heat in the first member, supplying an adhesive, pressing the second member against the first, storing heat in the second member, supplying an adhesive and successively adding other members to form a series, and setting the adhesive by the stored heat, the pressure applied to the later assembled members being transmitted to the earlier 100 assembled members.

12. A method of forming composite bodies consisting of more than two members, which comprises storing heat in the first member, applying an adhesive to a second member, 105 pressing the second member against the first, storing heat in the second member, applying an adhesive to a third member, pressing said third member against the second member and successively adding other such members, and setting the adhesive by the stored heat, the pressure applied to the later assembled members being transmitted to the earlier assembled members.

13. A continuous method of gluing, which 115 comprises supplying heat to at least one of the pieces to be joined, supplying an adhesive softening fluid and a heat-settable adhesive base to another piece, assembling, and while the adhesion develops, progressing the assem- 120 130

blage through a pressing zone, and setting the adhesive by the stored heat.

14. A continuous method of gluing, which comprises supplying heat to at least one of the pieces to be joined, supplying a heat-settable adhesive base, assembling, and while the adhesion develops, progressing the assemblage through a pressing zone, and setting the adhesive by the stored heat.

15. A method of gluing, which comprises supplying heat to at least one of the pieces to be joined and supplying a heat-settable adhesive to at least one of the pieces to be joined, assembling, and subjecting the assemblage to pressure before the stored heat has been materially dissipated, whereby the setting of the adhesive occurs under the influence of stored heat.

16. A method of gluing which comprises applying heat to one of the surfaces to be joined, supplying an adhesive to another surface, assembling and subjecting the assemblage to pressure before the stored heat has been materially dissipated, and setting the adhesive by the stored heat.

17. A method of forming composite bodies consisting of more than two members, which comprises storing heat in a surface of a first member, applying an adhesive to a surface of a second member, pressing the coated surface of the second member against the hot surface of the first member, storing heat in the opposite surface of the second member, applying an adhesive to a surface of a third member, pressing the coated surface of the third member against the hot surface of the second member, storing heat in the opposite surface of the third member, and successively and similarly incorporating additional members.

18. A method of forming composite bodies consisting of more than two members, which comprises storing heat in a surface of a first member, applying an adhesive to a surface of a second member, pressing the coated surface of the second member against the hot surface of the first member and simultaneously storing heat in the opposite surface of the second member, applying an adhesive to a surface of a third member, pressing the coated surface of the third member against the hot surface of the second member and simultaneously storing heat in the opposite surface of the third member, and successively and similarly incorporating additional members.

In testimony whereof we hereto affix our signatures.
